(57) **CLAIM**

The ornamental design for a cooking basket as shown and described.

DESCRIPTION

FIG. 1 is a front perspective view of a first embodiment of a cooking basket, showing my new design;

FIG. 2 is a rear perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof;

FIG. 8 is a bottom view thereof;

FIG. 9 is a front view of a second embodiment of a cooking basket, showing my new design;

FIG. 10 is a front view of a third embodiment of a cooking basket, showing my new design;

FIG. 11 is a front view of a fourth embodiment of a cooking basket, showing my new design;

FIG. 12 is a front view of a fifth embodiment of a cooking basket, showing my new design;

FIG. 13 is a front view of a sixth embodiment of a cooking basket, showing my new design;

FIG. 14 is a front view of a seventh embodiment of a cooking basket, showing my new design;

FIG. 15 is a front view of an eighth embodiment of a cooking basket, showing my new design; and

FIG. 16 is a front view of a ninth embodiment of a cooking basket, showing my new design; and,

FIG. 17 is a front view of the cooking basket of FIG. 1 showing a ninth alternative perforation pattern.

The broken lines in the drawings illustrate portions of the cooking basket that form no part of the claimed design.
